COMBINED FIRE EXTINGUISHING AND
SPACE VENTILATING DEVICE

Hilding V. Williamson and James C. Hesson, Chicago, Ill., assignors to Cardox Corporation, Chicago, Ill., a corporation of Illinois

Application June 5, 1947, Serial No. 752,658

12 Claims. (Cl. 169—5)

1

This invention relates to new and useful improvements in a combined fire extinguishing and space ventilating device.

In fighting fires burning in mines, tunnels, buildings used for industrial or residential purposes, and the like, firemen are confronted with the principal problems of locating the fire under extremely adverse visibility and respiration conditions due to the presence of dense smoke; directly applying the extinguishing medium onto the exposed surfaces of the objects being consumed by the fire; and introducing the extinguishing medium into inaccessible spaces or zones, such as hollow partitions, walls or floors, ventilating ducts, chimneys, or the like, in which the fires are burning.

It is the primary object of this invention to provide a combined discharge device or nozzle assembly which, when attached to the end of a hose-line supplied with liquid carbon dioxide from a suitable source, can be employed for ventilating a room, tunnel, mine, or the like, to improve visibility and respiratory conditions for the firemen by displacing or exhausting the smoke and other gases; for directly applying the carbon dioxide to the exposed surfaces of combustible objects, or bodies of inflammable liquids, being consumed by the fire and to the exposed surfaces of surrounding objects or masses which have become overheat to effect extinguishment of the fire and to cool off all of said objects and masses to a temperature below the reignition temperature of the combustible objects and liquids; and for delivering the carbon dioxide to the interior of inaccessible spaces or zones to extinguish fires burning therein.

A further object of the invention is the provision of a nozzle assembly which is operable to effect either the delivery of a mixture of carbon dioxide, snow and vapor for direct application onto a fire, or the movement of a large volume of air, by means of a relatively small aspirating discharge of carbon dioxide, to bring about ventilation of rooms, tunnels, mines, or the like.

Still another object of the invention is to provide a discharge device which can be employed for extinguishing a fire burning in an inaccessible space, such as a hollow partition, wall, or floor, a ventilating duct, a chimney, or the like, either by delivering carbon dioxide only to the interior of such a space to effect the complete extinguishment by the smothering and cooling action of the carbon dioxide, or by simultaneously delivering the carbon dioxide to the interior of such a space, as aforesaid, and directing against the exposed

2

exterior of the partition, wall, floor, etc., a large volume of air, that is propelled by a separate discharge of carbon dioxide, to assist in cooling the involved combustible material to a temperature below its reignition point.

A still further object of the invention is the provision of a discharge nozzle which can be operated to effect the delivery of carbon dioxide at different rates.

10 Other objects and advantages of the invention will be apparent during the course of the following description.

In the accompanying drawings forming a part of this specification and in which like numerals are employed for designating like parts throughout the same,

Figure 1 is a partly side elevational view and partly longitudinal sectional view of a combined fire extinguishing and space ventilating device 20 that embodies this invention,

Figure 2 is a transverse sectional view taken on line 2—2 of Fig. 1,

Figure 3 is a transverse sectional view taken on line 3—3 of Fig. 1,

25 Figure 4 is a similar view to Fig. 1 but illustrates a modification of the invention,

Figure 5 is a transverse sectional view taken on line 5—5 of Fig. 4, and

Figure 6 is a transverse sectional view taken on line 6—6 of Fig. 4.

In the drawings, wherein for the purpose of illustration are shown the preferred embodiments of this invention, and first particularly referring to Figs. 1 to 3 inclusive, the reference character 7

35 designates a pipe-line that is adapted to be connected to a suitable source of supply of liquid carbon dioxide by means of a flexible hose line, or the like, not shown. The pipe-line 7 is illustrated in Fig. 1 as being formed with two outlet ends or branches 8 and 9 which are arranged in parallelism at their outer end portions or extremities.

40 The outlet end or branch 8 is connected to the valve 10, of conventional design, that is provided with a valve body operating stem 11 projecting

45 from the casing of the valve. The valve 10, preferably, is of the spring-seated disc type so that the valve stem 11, normally, will occupy the position illustrated in Fig. 1 and the disc body will be seated to prevent flow of carbon dioxide through the valve. A mounting arm or bracket 12 projects laterally from the casing of the valve 10 and has pivotally connected to its outer end the squeeze-grip operating lever 13. When the free end portion of this lever is moved toward the

pipe-line 7, the valve 10 will be opened to allow carbon dioxide to pass therethrough.

A pipe section 14 is connected to the outlet side of the valve 10 and is formed at its outer end portion with a nozzle tip 15. The bore of the pipe section 14 and tip 15 is of special design. That is to say, the bore is reduced in diameter to form the reduced orifice 16. Axially outwardly of this orifice, the bore is of conical shape, or flares outwardly, at 17. This bore construction is provided so that the carbon dioxide delivered to the bore of the pipe section will be maintained in its liquid phase, due to the back pressure developed by the reduced orifice 16 which will retain the carbon dioxide at a pressure in excess of 75 pounds per square inch, absolute. The liquid carbon dioxide, in passing through the restricted orifice 16 and the flared bore portion 17, will be permitted to expand to atmospheric pressure and will be converted to a mixture of snow and vapor. The snow and vapor mixture, of course, will be discharged from the outer open end of the nozzle tip 15 as a jet or stream of relatively high velocity.

Supported on the nozzle tip 15 by means of the four radial fins 18, see Figs. 1 and 3, is a tubular shield 19. This shield is of cylindrical shape throughout the major portion of its length; is entirely open at its outer end 20, and is provided with an outwardly flared, open inner end 21. By inspecting Fig. 1, it will be seen that the shield 19 is so mounted on the nozzle tip 15 that the tip is concentrically positioned in the flared inner end portion of the shield and will direct the discharged jet or stream of mixed carbon dioxide vapor and snow axially of the shield 19 for release from the open outer end 20 of the shield. The discharge extremity of the nozzle tip 15 is intended to be so located with respect to the open, flared end 21 of the shield that the discharged, relatively high velocity, jet or stream of carbon dioxide will suck or aspirate a substantial volume of air from the surrounding atmosphere into the flared end of the shield for discharge through the outer end 20 with the carbon dioxide that is released from the nozzle tip 15.

The nozzle tip 15 and shield 19 should be so proportioned and arranged that approximately 50 volumes of air will be caused to travel through the shield 19 for each volume of carbon dioxide that is released into the shield from the discharge end of the nozzle tip 15. When operated in this way, it will be apparent that the apparatus so far described can be very successfully employed for ventilating rooms, tunnels, mines, or the like, to dispel or displace, and often times to exhaust, the dense smoke that is almost always present in the vicinity of a fire. The apparatus, therefore, is extremely efficient as a portable device for displacing the dense smoke from the vicinity of a fire so that the operator of the apparatus can more readily locate the seat of the fire.

After the smoke, and other gases, have been displaced, to improve visibility and respiratory conditions for the firemen, the apparatus can be employed for applying only the carbon dioxide vapor and snow mixture directly on the fire by closing the inner, flared end 21 of the shield 19. When the inner end of the shield is closed, it will act as a "horn" for preventing entrainment of air by the snow and vapor mixture flowing through the bore of the shield. By the time the carbon dioxide snow and vapor mixture has reached the discharge end 20 of the shield 19, its

velocity will have been reduced to such an extent that very little if any air will be entrained from the surrounding atmosphere by the carbon dioxide discharged from the shield.

To enable the flared end 21 of the shield to be closed when desired, a disc or plate 22 is provided and is slidably mounted on the pipe section 14 by means of the sleeve 23. Fitted over this sleeve is a handle 24 that is formed of any suitable insulating material. This handle 24 is formed with a bead 25 at its inner end which is engageable by the latch 26 for restraining the handle, and its associated disc or plate 22, in the dotted line position illustrated in Fig. 1. When 10 in this retracted position, the disc or plate 22 will not close the flared inner end 21 of the shield 19 and the apparatus can be employed to effect ventilation of a room, tunnel, mine, or the like. When the disc or plate 22, and its associated handle 24 20 and sleeve 23, are in the full line position of Fig. 1, no air will be drawn into the flared open end 21 of the shield and the apparatus will function as a fire extinguishing nozzle or discharge device by means of which a mixture of carbon dioxide 25 snow and vapor can be directly applied to a fire. The low pressure, or partial vacuum, that will be established in the flared inner end portion of the shield, inwardly of the disc or plate 22, will function to tightly hold the periphery of 30 the disc plate 21 in contact with the curved inner surface of the flared end portion 21 of the shield 19.

The outlet end or branch 9 of the pipe-line 7 has connected thereto a second valve 27 which is 35 of the same construction as the previously described valve 10. This valve 27, therefore, has the projecting stem 28 that is operated by the squeeze-grip lever 29 pivotally mounted on the bracket or arm 30 projecting laterally from the 40 casing of the valve 27.

A discharge tube 32 of any desired length is 45 connected to the discharge side of the valve 27 and extends in close parallelism with the shield 19. Fins 33 and 34 are provided for inter-connecting the shield 19 and the tube 32 so that each 50 one of these last two mentioned elements will brace and reinforce the other. It will be appreciated that if the shield 19 were not braced by the tube 30 it would not be strong enough to withstand the rough handling fire extinguishing apparatus normally is subjected to.

The outer end of the discharge tube 32 is closed by the pointed plug 35. Inwardly of this plug, the end portion of the tube 32 is provided with 55 any desired number of laterally opening ports 36 through which carbon dioxide may be released to form a discharge of snow and vapor for fire extinguishing purposes.

Firemen very frequently are confronted with 60 the problem of extinguishing a fire that is burning in inaccessible spaces or zones, such as hollow partitions, walls or floors, ventilating ducts, chimneys, or the like. When conventional discharge apparatus is employed in an endeavor to 65 extinguish such an inaccessible fire, it is necessary for the firemen to chop a hole through the exposed side of the space or zone to permit the fire extinguishing medium to be introduced.

The sharpened end plug 35 of the tube 32 is 70 employed for piercing the exposed side of the inaccessible space or zone in which the fire is burning so that the discharge ports 36 may be located in said space or zone. When so positioned, opening of the valve 27 will permit the carbon dioxide 75 discharge of snow and vapor to be released into

the space or zone for effecting extinguishment of the fire.

It will be appreciated by those experienced in the art that fires are extinguishable either by smothering the fire, so that the combustible material being consumed will not be provided with sufficient oxygen to support combustion, or by cooling the combustible material so as to lower its temperature below the ignition point of the material. Fires burning in inaccessible spaces or zones, such as hollow partitions, walls, floors, or the like, usually are detected or indicated by the heating of the exposed sides of said spaces or zones. Consequently, the pointed end of the discharge tube 32 should be forced through the hottest part of the exposed side so that the discharged carbon dioxide will be delivered at the seat of the fire.

It has been determined that extinguishment of a fire burning in hollow partitions, walls, or floors and ventilating ducts, chimneys, or the like, can be more readily and rapidly accomplished if a heat absorbing fluid is caused to flow over the exposed side of the inaccessible space or zone through which the pointed end of the discharge tube 32 has been forced. Therefore, while the discharge tube 32 is being employed for delivering fire extinguishing carbon dioxide to the interior of the inaccessible space or zone, the nozzle tip 15 and shield 19 may be employed for impinging a heat absorbing fluid against the exposed side of said space or zone. Ordinarily, the shield 19 will be employed for this purpose with its inner end left open so that the heat absorbing fluid will be air that is projected by the discharge of carbon dioxide from the nozzle tip 15. The temperature of the air that is expelled from the outer end of the shield 19, of course, will be lowered substantially by its contact with the extremely cold carbon dioxide that is discharged from the nozzle tip 15. However, if the fire has actually burnt through the exposed side of the inaccessible space or zone, the inner flared end 21 of the shield 19 may be closed by the plate or disc 22 so that nothing but a mixture of carbon dioxide snow and vapor will be discharged from the outer end 20 of the shield to effect extinguishment of the exposed fire.

The combined fire extinguishing and space ventilating device of Figs. 4 to 6 inclusive differs from the device of Figs. 1 to 3 inclusive only by the provision of a different form of valve, and its operating mechanism, for the nozzle tip so that the rate of discharge of carbon dioxide from this tip can be varied. Consequently, new reference characters only will be applied to the elements that differ structurally from those already described in connection with Figs. 1 to 3 inclusive.

The supply pipe-line 7a has connected thereto the T-coupling 37 to which the outlet end or branch 8a and the outlet or branch 9a are connected.

A T-shaped casing 38 is connected to the outer end of the outlet or branch 8a. In one opening of this casing 38 the pipe section 14a is connected. The outer end of this pipe section is properly shaped to provide the nozzle tip 15a that is formed with a conical or flared bore portion 17a. A restricted orifice and tapered valve seat 16a, also, is formed in the bore of the nozzle tip 15a.

Associated with this orifice and seat 16a is a needle valve 39 that is carried by the long stem 40 which extends through the bore of the pipe section 14a and the casing 38. Guide vanes 41 are formed on the stem 40 adjacent the needle valve

39 to support the needle valve at all times concentrically with the valve seat and orifice 16a.

The remaining opening of the casing 38 has fastened therein the hollow plug 42 through which projects the outer end of the valve stem 40. Packing material 43 is positioned in the bore of the plug 42 and is compressed by the packing nut 45 to prevent leakage of carbon dioxide around the valve stem 40. A stop pin 46 is passed through the valve stem 40 to provide a seat for one end of the compression spring 47 that surrounds the valve stem 40 and bears at its other end against the inner face of the plug 42. It will be appreciated, therefore, that the spring 47 and seat 46 will function normally to urge the needle valve 39 toward the cooperating surface of the combined orifice and valve seat 16a.

The outer end of the valve stem 40 has connected thereto one arm of the squeeze-grip lever 48 which is employed for moving the needle valve 39 away from the valve seat and orifice 16a. This lever 48 is supported by a bracket arm 49 that is formed on the plug 42.

With this needle valve mechanism, it will be appreciated that the rate of discharge of carbon dioxide from the end of the nozzle tip 15a may be varied to any extent desired by proper manipulation of the operating lever 48, and that discharge of the carbon dioxide may be stopped entirely by releasing the lever 48 and permitting the spring 47 to completely seat the needle valve 39. This control over the rate of discharge of the carbon dioxide from the nozzle tip 15a into the shield 19 is a very desirable feature because it permits different rates of flow of carbon dioxide to be employed for effecting the extinguishment of fires and for effecting the ventilation of rooms, tunnels, mines, or the like.

In this assembly, the same plate or disc 22, and its supporting sleeve 23 and operating handle 24, are provided for controlling the flared open end 21 of the tubular shield 19.

All of the remaining elements of this combined discharge apparatus are the same as those described in connection with the embodiment of the invention illustrated in Figs. 1 to 3 inclusive and, for that reason, the same reference numerals will be applied thereto without repeating the description of the same.

It is to be understood that the apparatus shown in Figs. 4 to 6 inclusive will function in the same manner as the apparatus disclosed in Figs. 1 to 3 inclusive for extinguishing fires and ventilating such spaces as rooms, tunnels, mines or the like.

It is to be understood that the forms of this invention herewith shown and described are to be taken as preferred examples of the same, and that various changes in the shape, size, and arrangement of parts may be resorted to without departing from the spirit of the invention or the scope of the subjoined claims.

Having thus described the invention, we claim:

1. A fire extinguishing and space ventilating device of the type described, comprising a pipe section adapted to be connected to a source of supply of liquid carbon dioxide, a nozzle tip on the end of the pipe section for releasing the carbon dioxide as a relatively high velocity jet, a tubular shield open at both ends, means for mounting the nozzle tip in the open inner end portion of the shield so as to direct its jet of carbon dioxide longitudinally of the shield for discharge to the atmosphere from its open outer end, means for opening and closing the inner 70 open end of the shield at the will of the operator,

and valve means for controlling the flow of carbon dioxide through the pipe section.

2. A fire extinguishing and space ventilating device of the type described, comprising a pipe section adapted to be connected to a source of supply of liquid carbon dioxide, a nozzle tip on the end of the pipe section for releasing the carbon dioxide as a relatively high velocity jet, a tubular shield open at both ends and having one open end flared outwardly, means for mounting the nozzle tip in the bore of the tubular shield adjacent its flared end portion so as to direct the jet of carbon dioxide longitudinally of the shield for discharge to the atmosphere from its remaining open end, a disc slidably mounted on the pipe section for movement into and out of a position for closing the flared open end of the shield, and valve means for controlling the flow of carbon dioxide through said pipe section.

3. A fire extinguishing and space ventilating device of the type described, comprising a pipe section adapted to be connected to a source of supply of liquid carbon dioxide, a nozzle tip on the end of the pipe section for releasing the carbon dioxide as a relatively high velocity jet, a tubular shield open at both ends, means for mounting the nozzle tip concentrically in the open inner end portion of the shield so as to direct its jet of carbon dioxide axially of the shield for discharge to the atmosphere from the open outer end of the shield, a plate slidably mounted on the pipe section for movement into and out of a position for closing the inner open end of the shield, an insulated handle connected to the slidable plate for moving the latter, latch means for restraining movement of the plate when it is out of its position for closing the inner open end of the shield, and valve means for controlling the flow of carbon dioxide through said pipe section.

4. A fire extinguishing and space ventilating device of the type described, comprising a pipe section adapted to be connected to a source of supply of liquid carbon dioxide, a nozzle tip on the end of the pipe section for releasing the carbon dioxide as a relatively high velocity jet, a tubular shield open at both ends and having one of its open ends flared outwardly, means for mounting the nozzle tip concentrically in the bore of the tubular shield adjacent its flared end portion so as to direct its jet of carbon dioxide axially of the shield for discharge to the atmosphere from the remaining open end, a disc slidably mounted on the pipe section for movement into and out of a position for closing the flared open end of the shield, an insulated handle slidable along the pipe section with the said disc, means mounted on the pipe section and engageable with said handle for restraining movement of the disc when the latter is out of its position for closing the flared open end of the shield, and valve means for controlling the flow of carbon dioxide through said pipe section.

5. A fire extinguishing and space ventilating device of the type described, comprising a pipe section adapted to be connected to a source of supply of liquid carbon dioxide, a nozzle tip on the end of the pipe section for releasing the carbon dioxide as a high velocity jet, a tubular shield open at both ends, means for mounting the nozzle tip concentrically in the open inner end portion of the shield so as to direct its jet of carbon dioxide axially of the shield for discharge to the atmosphere from its open outer end, a plate slidably mounted on the pipe section for movement into and out of a position for closing the inner open end of the shield, a discharge tube connected to the remaining valve and arranged to extend in close parallelism with the tubular shield and to terminate beyond its outer open end, said tube having laterally opening carbon dioxide discharge ports formed in its outer end portion and having a pointed plug closing its outer end, and reinforcing means connecting the tubular shield to said discharge tube.

6. A fire extinguishing and space ventilating device of the type described, comprising a pipe section adapted to be connected to a source of supply of liquid carbon dioxide, a nozzle tip on the end of the pipe section for releasing the carbon dioxide as a relatively high velocity jet, a tubular shield open at both ends and having one of its open ends flared outwardly, means for mounting the nozzle tip concentrically in the bore of the tubular shield adjacent its flared end portion so as to direct its jet of carbon dioxide axially of the shield for discharge to the atmosphere from the remaining open end, a disc slidably mounted on the pipe section for movement into and out of a position for closing the flared open end of the shield, said nozzle tip having a tapered valve seat formed in its bore, a needle valve slidable in the bore of the pipe section and having a stem extending exteriorly of the pipe section, and a handle for manipulating the valve stem to adjust the needle valve relative to its seat to vary the rate of discharge of carbon dioxide from the nozzle tip.

10 7. A fire extinguishing and space ventilating device of the type described, comprising a pipe section adapted to be connected to a source of supply of liquid carbon dioxide, a nozzle tip on the end of the pipe section for releasing the carbon dioxide as a relatively high velocity jet, a tubular shield open at both ends and having one of its open ends flared outwardly, means for mounting the nozzle tip concentrically in the bore of the tubular shield adjacent its flared end portion so as to direct its jet of carbon dioxide axially of the shield for discharge to the atmosphere from the remaining open end, a disc slidably mounted on the pipe section for movement into and out of a position for closing the flared open end of the shield, said nozzle tip having a tapered valve seat formed in its bore, a needle valve slidable in the bore of the pipe section and having a stem extending exteriorly of the pipe section, and a handle for manipulating the valve stem to adjust the needle valve relative to its seat to vary the rate of discharge of carbon dioxide from the nozzle tip.

15 8. A fire extinguishing and space ventilating device of the type described, comprising a pipe section adapted to be connected to a source of supply of liquid carbon dioxide and having two outlet branches, a manually operable valve connected to each branch outlet, a pipe section connected to one of said valves, a nozzle tip on the end of the pipe section for releasing carbon dioxide as a relatively high velocity jet, a tubular shield open at both ends, means for mounting the shield on the nozzle tip with the latter positioned concentrically in the open inner end portion of the shield so as to direct its jet of carbon dioxide axially of the shield for discharge to the atmosphere from its outer open end, a discharge tube connected to the remaining valve and arranged to extend in close parallelism with the tubular shield and to terminate beyond its outer open end, said tube having laterally opening carbon dioxide discharge ports formed in its outer end portion and having a pointed plug closing its outer end, and reinforcing means connecting the tubular shield to said discharge tube.

20 9. A fire extinguishing and space ventilating device of the type described, comprising a pipe section adapted to be connected to a source of supply of liquid carbon dioxide and having two outlet branches, a manually operable valve connected to each one of said outlet branches, a pipe section connected to one of said valves, a nozzle tip on the end of the pipe section for releasing carbon dioxide as a relatively high velocity jet, a tubular shield open at both ends, means for mounting the shield on the nozzle tip with the latter positioned concentrically in the open end portion of the shield so as to direct its jet of carbon dioxide axially of the shield for discharge to the atmosphere from its outer open end, a plate slidably mounted on the pipe section for movement into and out of a position for closing the inner open end of the shield, a discharge tube connected to the remaining valve and arranged to extend in close parallelism with the tubular shield and to terminate beyond its outer

open end, said tube having laterally opening carbon dioxide discharge ports formed in its outer end portion and having a pointed plug closing its outer end, and reinforcing means connecting the tubular shield to said discharge tube.

9. A fire extinguishing and space ventilating device of the type described, comprising a pipeline adapted to be connected to a source of supply of liquid carbon dioxide and having two outlet branches, a manually operable valve connected to each outlet branch, a pipe section connected to one of said valves, a nozzle tip on the end of the pipe section for releasing carbon dioxide as a relatively high velocity jet, a tubular shield open at both ends, means for mounting the shield on the nozzle tip with the latter positioned concentrically in the open inner end portion of the shield so as to direct its jet of carbon dioxide axially of the shield for discharge to the atmosphere from its outer open end, a discharge tube connected to the remaining valve, said tube having laterally opening carbon dioxide discharge ports formed in its outer end portion, and a pointed plug closing the outer end of the tube.

10. A fire extinguishing and space ventilating device of the type described, comprising a pipeline adapted to be connected to a source of supply of liquid carbon dioxide and having two outlet branches, a pipe section connected to one of said outlet branches, a nozzle tip on the end of the pipe section for releasing carbon dioxide as a relatively high velocity jet, tubular shield open at both ends, means for mounting the nozzle tip concentrically in the open inner end portion of the shield so as to direct its jet of carbon dioxide axially of the shield for discharge to the atmosphere from its open outer end, a plate slidably mounted on the pipe section for movement into and out of a position for closing the inner open end of the shield, said nozzle tip having a tapered valve seat formed in its bore, a needle valve slideable in the bore of the pipe section and having a stem extending exteriorly of the pipe section, a handle for manipulating the valve stem to adjust the needle valve relative to its seat to vary the rate of discharge of carbon dioxide from the nozzle tip, a manually operable valve connected to the remaining outlet branch, a discharge tube connected to the manually operable valve and arranged to extend in close parallelism with the tubular shield and to terminate beyond its outer open end, said tube hav-

ing laterally opening carbon dioxide discharge ports formed in its outer end portion and having a pointed plug closing its outer end, and reinforcing means connecting the tubular shield to said discharge tube.

5 11. A fire extinguishing and space ventilating device of the type described, comprising a pipeline adapted to be connected to a source of supply of liquid carbon dioxide and having two outlet branches, a pipe section connected to one of said branches, a nozzle tip on the end of the pipe section for releasing carbon dioxide as a relatively high velocity jet, a tubular shield open at both ends, means for mounting the shield on the nozzle tip with the latter positioned concentrically in the open inner end portion of the shield so as to direct its jet of carbon dioxide axially of the shield for discharge to the atmosphere from its outer open end, and a discharge tube connected to the remaining branch and arranged to extend in close parallelism with the tubular shield and to terminate beyond its outer end, said tube having laterally opening carbon dioxide discharge ports formed in its outer end portion and having a pointed plug closing its outer end.

10 12. A fire extinguishing and space ventilating device of the type described, comprising a pipe section adapted to be connected to a source of supply of liquid carbon dioxide, a nozzle tip on the end of the pipe section for releasing the carbon dioxide as a relatively high velocity jet, a tubular shield open at both ends, means for mounting the nozzle tip in the open inner end portion of the shield so as to allow air to enter said open inner end and so as to direct its jet of carbon dioxide longitudinally of the shield for discharge to the atmosphere from its open outer end, means in addition to the nozzle tip mounting means for opening and closing the inner open end of the shield, and valve means for controlling the flow of carbon dioxide through the pipe section.
